PEANUT BUTTER DISPENSER

Saul R. Rosenberg, Los Angeles, Calif., assignor to Food Corporation of America, Los Angeles, Calif., a corporation of California

Filed Oct. 3, 1961, Ser. No. 66,955

Term of patent 3½ years

(Cl. D52—3)

The undisclosed side of the peanut butter dispenser is substantially the same in appearance as the side shown in FIG. 2, except that the side panel has no opening or door as shown in FIG. 2.

The showing of the paper cups and container caps in broken lines is depicted for illustrative purposes only.

I claim:

The ornamental design for a peanut butter dispenser, as shown and described.
